(57) **CLAIM**

The ornamental design for an side element of a shoe upper,
as shown and described.

DESCRIPTION

FIG. 1 is a perspective view of an element of a shoe upper
showing the new design;

FIG. 2 is a side elevational view thereof;

FIG. 3 is a perspective view of an alternative embodiment of
the shoe upper of the new design; and,

FIG. 4 is a side elevational view of the alternative embodiment.

The even broken lines in FIGS. 1 and 2 represent design
elements. The uneven broken lines surrounding the design
element represent the bounds of the claimed design. The
uneven broken lines in all figures showing the remainder of
the shoe are for illustrative purposes only and form no part
of the claimed design.
